UNITED STATES PATENT OFFICE.

FRANK M. KLEINE, OF DULUTH, MINNESOTA.

WIRE-CLAMP.

1,216,575.

Specification of Letters Patent. Patented Feb. 20, 1917.

Application filed July 15, 1915. Serial No. 40,100.

To all whom it may concern:

Be it known that I, FRANK M. KLEINE, a citizen of the United States, residing at Duluth, in the county of St. Louis and State 5 of Minnesota, have invented certain new and useful Improvements in Wire-Clamps, of which the following is a specification.

This invention relates to an improved wire clamp whereby a wire forming part of 10 a fence can be connected with the fence post and the principal object of the invention is to provide a clamp which can be connected with a cement or iron fence post and which is provided with an improved clutching 15 element for securely engaging the fence wire and holding the wire in the tightened condition.

Another object of the invention is to so 20 construct the two clutching jaws that when the wire is gripped it will be bent downwardly thus preventing the wire from slipping.

Another object of the invention is to so 25 construct the clamp as to permit of its being cast, thus permitting the clamp to be very cheaply produced.

This invention is illustrated in the accompanying drawings, wherein:—

Figure 1 is a view showing the clamp in 30 side elevation and embedded in a post a fragment of the same being shown in section.

Fig. 2 is a view showing the clamp in front elevation.

Fig. 3 is a view showing the clamp principally in elevation, the stationary jaw being broken away to show the manner of gripping the wire.

Fig. 4 is a view showing the clamp in 40 vertical section.

This clutch or fastener includes the stationary jaw 10 and movable jaw 11 which is pivotally connected with the stationary jaw by means of the rivet 12, the movable jaw 45 being provided with an extension 13 cut to resemble a nut so that the movable jaw can be turned to an operative or inoperative position. The stationary jaw which is connected with the post 14 by means of the threaded stem or shank 15 is provided with 50 a flange 16 having a lip 17 and provided

with a toothed gripping face 18 which is curved as shown in Fig. 3 so that a pocket is formed into which the wire 19 will be bent when the toothed gripping face 20 of the 55 movable jaw is in engagement with the wire.

This clutch is connected with the post either by embedding the shank 15 in the cement while forming the post or by screwing the shank through a threaded opening 60 in an iron post and the movable jaw is then swung out of the position shown in the drawing so that the wire can be passed across the pocket of the stationary jaw and stretched tight. After the wire has been 65 stretched tight a wrench will be connected with the lug or extension 13 and the movable jaw swung to the position shown thereby bringing its gripping face into engagement with the wire to bend the wire into 70 the pocket. The wire will then be securely gripped by the gripping faces 18 and 20 of the two jaws and the wire will be securely held in place and prevented from slipping. It should be noted that the 75 threaded stem 15 extends from the body portion 10 opposite the free end of the movable jaw and therefore when the device is in use, the wire which is under tension cannot turn the stem in the post. With this 80 construction, the clamp will be securely connected with the post without the necessity of two or more fasteners. The lip 17 prevents any danger of the wire slipping out of the pocket from between the jaws by a 85 transverse movement and therefore the wire cannot become disconnected from the clutch until the movable jaw is again moved into the inoperative position. It will thus be seen that this clutch is so constructed that 90 the wire will be securely but releasably held in engagement with the post.

What is claimed is:—

A clamp comprising a body portion, a flange extending outwardly from the lower 95 portion of said body portion and constituting a stationary jaw having a longitudinally curved upper gripping face having transversely extending gripping teeth, a movable jaw pivotally connected with the body portion above the stationary jaw and provided with a curved free end face conforming to 100

the curvature of the gripping face of the stationary jaw and provided with transversely extending gripping teeth, and a threaded stem extending from the body 5 portion opposite the free end of the movable jaw when the movable jaw is in an operative position.

In testimony whereof I affix my signature in presence of two witnesses.

FRANK M. KLEINE.
